US00D840158S

(12) **United States Design Patent** (10) **Patent No.:** **US D840,158 S**
(45) **Date of Patent:** **** Feb. 12, 2019**

(54) **ORAL CARE IMPLEMENT**

(71) Applicant: **Colgate-Palmolive Company**, New York, NY (US)
(72) Inventors: **Wen Jin Xi**, Shanghai (CN); **Bo Zhang**, Yangzhou (CN); **Yanmei Ji**, Yangzhou (CN); **Xiangji Ding**, Yangzhou (CN); **Jianrong Zhou**, Yangzhou (CN)

(73) Assignee: **Colgate-Palmolive Company**, New York, NY (US)

(**) Term: **15 Years**

(21) Appl. No.: **29/586,606**

(22) Filed: **Dec. 6, 2016**

Related U.S. Application Data

(62) Division of application No. 29/533,953, filed on Jul. 23, 2015, now Pat. No. Des. 776,436.
(51) **LOC (11) Cl.** **04-02**
(52) **U.S. Cl.** **D4/104**

CLAIM

The ornamental design for an oral care implement, as shown and described.

DESCRIPTION

FIG. 1 is a front left perspective view of an oral care implement;

FIG. 2 is a rear right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the article that form no part of the claimed design.

1 Claim, 4 Drawing Sheets
